HEADBOARD

Ernest L. Swarts and Orville B. Solie, Rockford, Ill., assignors to The Lane Company, Inc., Altavista, Va., a corporation of Virginia

Filed Nov. 2, 1959, Ser. No. 58,170

Term of patent 14 years

(Cl. D5—4)

Fig. 2.

The essential features of the design are shown in solid lines. The back of the headboard is conventionally plain.

We claim:

The ornamental design for a headboard, as shown and described.
